UNITED STATES PATENT OFFICE.

ALFRED ARTHUR QUICK, OF CLIFTON HILL, AND CHRISTOPHER JAMES SPENCER, OF MELBOURNE, VICTORIA, AUSTRALIA.

DEVICE FOR CONTROLLING THE DELIVERY OF LIQUIDS FROM TANKS OR VESSELS.

1,070,288.

Specification of Letters Patent.

Patented Aug. 12, 1913.

Application filed December 22, 1908. Serial No. 468,845.

To all whom it may concern:

Be it known that we, ALFRED ARTHUR QUICK and CHRISTOPHER JAMES SPENCER, subjects of the King of Great Britain, residing at 46 Hilton street, Clifton Hill, driver, and 285 Swanston street, Melbourne, electrician, respectively, Victoria, Australia, have invented new and useful Improvements in Devices for Controlling the Delivery of Liquids from Tanks or Vessels, of which the following is a specification.

Our invention relates to an improved apparatus for controlling the delivery of liquids from a supply tank or vessel to a receiving can, and refers more particularly to a means for controlling the quantity of kerosene oil delivered from such tanks or vessels.

Though our invention is hereinafter described as relating to the control of the delivery of kerosene oil from a supply tank or vessel, it will be well understood it is equally applicable to the delivery of other liquids, and in this specification the term "oil" will be held to include such other suitable liquids.

With the supply of bulk kerosene oil, as at present practised, the oil is sent out in transport tanks from which it is delivered to the customers in measured cans adapted to contain a predetermined quantity.

Our invention consists of a tap device which is attached to the supply tank and is so constructed as to permit of its being operated only when connected to the receiving can or vessel, such connection serving to open the tap for the delivery of the liquid, the said tap device being closed by the operation of disconnecting it from the receiving vessel.

In order that our invention may be better understood we will now proceed to describe the same with reference to the accompanying sheet of drawings in which:—

Figure 1 is a side sectional elevation of our invention showing its connection to a receiving can or vessel adapted to contain a measured or predetermined quantity of liquid; and Fig. 2 is a detail view of certain parts thereof.

A is the receiving can or vessel, the top of which is formed with a lip or spout A' for

the purpose of conveniently discharging the liquid therefrom. Where the top part joins the body of the can A, there is disposed a collar A², provided with a cross web A³ having a screw-threaded socket A⁴, the aforesaid collar A² and the screw-threaded socket A⁴ constituting the means whereby the tap device which is attached to the supply tank may be connected to the receiving vessel A, whenever it is intended to draw liquid therefrom as hereinafter described. For this purpose the outflow pipe B' from the supply tank B is attached to an inlet pipe C' on a casing C within which the tap device is inclosed. Casing C is formed with a flange C² which bears upon collar A², a washer C³ of rubberized leather or other suitable material being interposed therebetween. The casing C is also formed with a downwardly projecting ring C⁴ which is inserted within the central opening in vessel A produced by the collar A², and the said ring C⁴ is provided with holes C⁵ for the flow of the liquid as hereinafter described. Ring C⁴ is provided with a swinging trigger C⁶, which is utilized to lock casing C to vessel A on being forced under collar A². Casing C extends upward in the form of a cylinder C⁷ within which works the device for opening and closing the tap for admitting the flow of the oil, said device being arranged in such manner that the means supplied for opening the tap and allowing of the flow of oil cannot be operated unless said casing is connected to the receiving vessel. For this purpose within the upwardly extending cylinder C⁷ is provided an internal cylindrical casing D having a hollow downward extension D' passing out through the bottom of the casing C. The extension D' is formed at its lower end with a plunger D² having a seat or washer of rubberized leather or other suitable material which engages the opening in the bottom of the casing C and thereby forms a valve or tap by which, when the same is lowered, the oil or other liquid is admitted to the interior of the receiving vessel through the holes C⁵, while, when it is raised, the flow of the liquid is cut off. Within the casing C⁷ and surrounding the internal casing D is a helical spring E which bears upon the flange

D² at the top, so that when said casing D is depressed, its downward movement is against the tension of the said spring. Plunger D² is designed for movement in a vertical direction, which movement is effected through the agency of a dome F, (shown in detail in Fig. 2) having one or more slots or grooves F' cut in the sides thereof, said dome F being adapted to fit within the internal casing D and being provided with an upwardly projecting sleeve F² that projects through the central opening in the top of the outer casing C¹. Sleeve F² is provided with an operating handle F³ by which it may be rotated. Within the dome F fits a hollow cup G having feathers G' (shown more particularly in Fig. 2), corresponding with the slots or grooves F' and adapted to engage the same, so that the same rotary motion may be transferred from the dome F to the cup G irrespective of their vertical positions. This cup G is provided with a downward projection G² having its pointed lower end G³ screw-threaded and adapted to engage threaded end G³ engaging the socket A⁴, in the cross bar or web A³. Thus, in operation, dome F is depressed against spring E, so as to insert point G³ of extension G² into socket A⁴, and to engage the slots F' with the feathers G' in the cup G; rotation of the drum by means of its handle will then occasion a similar movement of said cup. As the rotation of cup G continues, the screw-threaded end G³ engaging the socket A⁴, the cup G, and with it the internal casing D, will be drawn downward also, thereby compressing the spring E. At the same time, the plunger D² on the downward extension D' is forced away down from the opening in the casing C, thereby allowing of a flow of oil through the holes C⁵ into the interior of the vessel A from the supply vessel B. Instead of the screw G³ we may provide an equivalent device such as an eccentric or cam or the like by which the plunger D² is forced downward by the connection of the casing C with the vessel A. Simultaneously the trigger C⁶ is forced outward by the plunger D² and is caused to engage under the flange A², thereby locking the casing C on to the top of the vessel A, while the filling operation is proceeding, and preventing any tampering or interfering with such filling operation.

For the purpose of allowing of the outflow of air, during the filling operation, and of any surplus liquid, the downward extension G² is drilled with a passage G⁴ having parts G⁵ communicating with the interior of vessel A, the passage G⁴ extending upward into communication with the interior of the cup G. Within cup G fits a plunger H having packing rings H' and provided with an upwardly projecting hollow rod H² which extends through the sleeve F² and is con-

nected to a pipe J which communicates with the interior of the supply vessel B above the surface of the oil. The plunger H is also formed with a valve H³ which is adapted to cover the passage G⁴ in the downward extension G². Ports H⁴ are provided communicating with the hollow rod H². Thus the air within the vessel and any surplus liquid is allowed to flow upward through the passage G⁴ in the downward extension G² into the cup G, thence through the ports H⁴ into the hollow rod H², and finally through the latter and the pipe J back into the supply vessel, while the valve H³ prevents back flow.

In operation, it will be seen that the tap device is opened and closed by the raising and lowering of the downward extension D' of the inner cylindrical casing D, and the disengagement and engagement of the plunger D² from and with the opening in the bottom of the casing C. This is effected by the screw-threaded point G³ engaging the socket A⁴ and it is only by the casing C being connected in this way to the receiving vessel A that the oil can flow thereinto from the supply vessel B. Consequently, each filling operation of the receiving vessel A must be effected by manipulating the handle F³. As soon as the vessel A is filled, the flow is automatically cut off by the oil reaching the same level in the hollow tube H² or the pipe J as that within the vessel B. The casing C may then be removed and either connected in the same way to another similar receiving vessel, or to the same when emptied.

The device is all inclosed, as shown, so that it cannot be interfered with, and, as a further safeguard, the screw G³ may be incased within a cylinder, (not shown) which passes over the socket A⁴ when in engagement therewith.

Having fully described our invention, we claim:

1. In a liquid dispensing apparatus, the combination, with a supply vessel, and a receiving vessel; of a tap device attached to the first-named vessel and capable of connection to the neck of the second-named vessel, said device including an annular perforated member arranged to seat in said neck, and a member associated with the first-named member for covering and uncovering the perforations therein.

2. In a liquid dispensing apparatus, the combination, with a supply vessel, and a receiving vessel; of a support fitted in the neck of the second-named vessel; and a tap device attached to the first-named vessel and comprising stationary and movable members co-operating to form a cut-off, and a locking member carried by one of said members and operable by the other to engage

said support, for connecting said device to said neck.

3. In a liquid dispensing apparatus, the combination, with a supply vessel, and a receiving vessel; of a support fitted in the neck of the second-named vessel; and a tap device attached to the first-named vessel and adapted to rest upon said support, said device comprising an annular perforated member, a movable locking member carried thereby and arranged to engage said support, and a member associated with the first-named member for covering and uncovering the perforations therein and for operating 15 said locking member, to connect said device to said neck.

4. In a liquid dispensing apparatus, the combination, with a supply vessel, and a receiving vessel; of a support fitted in the neck of the second-named vessel and provided with a socket; and a tap device attached to the first-named vessel and associated with said support, said device comprising stationary and movable cut-off members having one end thereof adapted for engagement in said socket.

5. In a liquid dispensing apparatus, the combination, with a supply vessel, and a receiving vessel; of a collar fitted in the neck 30 of the second-named vessel and provided with a web having a threaded socket; and a tap device attached to the first-named vessel and supported upon said collar, said device comprising a stationary cut-off member, a 35 vertically movable cut-off member coacting therewith, and an operating member for the second-named cut-off member having a threaded end adapted for engagement in said socket.

40 6. The combination, with a receiving vessel, and a collar fitted in the neck thereof; of a cut-off supported upon said collar and comprising a stationary member provided with a locking member arranged to engage the collar, a movable member complementary to said stationary member and adapted to move said locking member into engagement with said support, and means for operating 45 said movable member.

50 7. The combination, with a receiving vessel, and a collar fitted in the neck thereof; of a cut-off supported upon said collar and comprising a stationary annular member provided with perforations, a locking member pivoted thereto, a movable member complementary to said stationary member for covering and uncovering the perforations in the latter and for moving said locking member into engagement with said collar, and means 55 for operating said movable member.

60 8. The combination, with a receiving vessel, and a collar fitted in the neck thereof; of a tap device supported upon said collar and comprising a cut-off composed of co-

acting stationary and movable member, 65 means associated with said movable member for normally holding the same in position to close the cut-off, and a depressible two-part element for operating said movable member to open the cut-off, the parts of said element 70 having a separable interlocking engagement with each other.

9. The combination, with a receiving vessel, and a collar fitted in the neck thereof and provided with a threaded socket; of a 75 tap device supported upon said collar and comprising a cut-off composed of coacting stationary and movable members, means associated with the latter member for normally holding the same in position to close 80 the cut-off, and a depressible two-part element having its lower part provided with a threaded end engaged in said socket, said parts having a separable interlocking engagement with each other, whereby they may 85 be rotated in unison to operate said movable member, for opening the cut-off.

10. In a liquid dispensing apparatus, the combination, with a supply vessel, and a receiving vessel having a support fitted in the 90 neck thereof; of a tap device attached to the first-named vessel and mounted upon said support, said device comprising a cut-off composed of stationary and movable members, a tubular member for operating the 95 movable cut-off member, a plunger associated with the operating member and provided with a hollow stem having a valve arranged to cover the bore of said operating member, and a pipe connection between said 100 stem and tank.

11. In an apparatus for controlling the delivery of liquids from a supply vessel to a receiving vessel, a tap device attached to the supply vessel and capable of being connected 105 to the receiving vessel, said device consisting essentially of a casing having a flange which fits within the neck of the said receiving vessel, said casing having a screw-operated plunger adapted to engage a socket 110 attached to said receiving vessel, and an operating member for said screw arranged at the top of the said casing, substantially as described.

12. In an apparatus for controlling the delivery of liquids from a supply vessel to a receiving vessel, the combination with a casing C and a movable plunger D² arranged therein and adapted to form therewith a valve for the control of the flow of 115 liquid, such valve being operated by the means for connecting and disconnecting the casing with the receiving vessel, of means for allowing of the outflow of air and the flow of any surplus liquid back into the supply vessel, consisting essentially of a hollow cup G, a channel G⁴ communicating with the interior of the receiving vessel and leading 125

into the interior of said cup G, a valve H³ for preventing the back flow, a hollow pipe H² with which said passage communicates, and a tube J to which said pipe is connected, 5 said tube discharging into the supply vessel above the level of the liquid, substantially as described.

In testimony whereof we have signed our

names to this specification in the presence of two subscribing witnesses.
